UNITED STATES PATENT OFFICE

2,002,366

METALLIC CABINET STRUCTURE

Hiroshi Eto, Tokyo, Japan, assignor to General
Electric Company, a corporation of New YorkApplication June 14, 1933, Serial No. 675,682
In Japan November 18, 1932

6 Claims. (Cl. 226—81)

My invention relates to metallic cabinet structures, such, for example, as are used for refrigerator cabinets.

It is desirable to provide metal refrigerator cabinets with joints which are hermetically sealed. When constructing refrigerator cabinets of thin sheet metal with welded joints it has been found difficult to form an air-tight joint by welding without heating the walls to such an extent as to cause warping. Spot welding may be employed with considerable success, but unless the welded spots overlap, the joints may not be air-tight.

Accordingly, it is an object of my invention to provide a welded sheet metal cabinet structure having welded joints which do not produce warping of the structure and having a seal for rendering the joints air-tight.

Another object of my invention is to provide a simple and efficient seal for sheet metal joints.

A further object of my invention is to provide an improved method for making an air-tight seal for metallic refrigerator cabinets employing welded joints.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing, in which Fig. 1 is a perspective view, partly in section, of the outer metallic shell of a refrigerator cabinet having a bottom wall secured to the side walls of the shell by a joint constructed in accordance with my invention; Fig. 2 is a sectional view of the joint shown in Fig. 1 at one stage of the construction thereof; and Fig. 3 is a sectional view of the completed joint shown in Fig. 1.

Referring to the drawing, in Fig. 1 I have shown the outer metal shell of a refrigerator cabinet comprising side walls 10, 11, 12 and 13 formed from a single metal sheet welded together at the ends. The front wall 13 is provided with a door opening 14 about which extend inturned flanges 15 of the wall. The tops of the walls 10, 11, 12 and 13 are provided with bent-over portions 16 extending about an opening 17 in the top of the cabinet through which a refrigerating cooling unit may be inserted, the bent-over portions 16 forming a seat on which a top for the cabinet may rest and support a refrigerating mechanism.

In accordance with my invention, the walls 10, 11, 12 and 13 are provided with flanges 18 turned

in at the bottom thereof about an opening 19 in the bottom of the cabinet, the flanges 18 being welded together at the corners along the line 20. A metal sheet or plate 21 having a peripheral flange 22 formed at right angles to the sheet as shown in Fig. 2, is placed within the cabinet and rests upon the flanges 18 at the bottom thereof, with the peripheral flange 22 extending upwardly, as shown. The flange 22 is spaced from the side walls 10, 11, 12 and 13 as shown in Fig. 2. When the plate 21 is in this position it is spot-welded to the flanges 18 to secure it rigidly to the remainder of the cabinet. In order to be sure that the joint formed between the plate 21 and flanges 18 will be air-tight, I place a continuous strip of any suitable resilient material 23 in the space between the walls 10, 11, 12 and 13 and the flange 22, and then bend the flange 22 outwardly against the strip of resilient material 23 and compress the strip tightly between the walls and flange 22. This continuous strip 23 may be made of a single strip having abutting or lapped ends such that a continuous seat is formed thereby. A cross section of the completed joint is shown in Fig. 3 and, as can be seen, the flange 22 has pressed the resilient strip 23 toward the wall 13 and has compressed it, and provided a considerable area on both sides of the strip 23 under pressure and in firm contact with wall 13 and the flange 22, which forms an air-tight joint.

By constructing the joints of a refrigerator cabinet in the manner described above, the advantages of a welded construction are obtained, and the disadvantage of warping of a metal cabinet structure due to overheating as in the fusion welding process is avoided, and an air-tight, or hermetically sealed joint is obtained. The method of forming this joint is extremely simple and results in greatly decreased cost of manufacture. The joint formed is neat and durable and admirably suited to the construction of refrigerator cabinets.

While I have described my invention in connection with the construction of the outer metal shell of a refrigerator cabinet, it will be apparent that it is applicable to other cabinet constructions, and I do not desire my invention to be limited to the specific embodiment shown and described, and I intend in the appended claims to cover all modifications thereof which do not depart from the spirit and scope of my invention.

What I claim as new and desire to secure by Letters Patent of the United States is:

1. A cabinet structure including a plurality of sheet metal walls, one of said walls having an

opening therein, a metal plate welded to said one wall within said structure and closing the opening in said wall, said plate having a peripheral flange spaced from the others of said walls, and means including resilient material between said flange and said walls for hermetically sealing said plate and said walls.

2. A cabinet including a plurality of metal walls, one of said walls having an opening therein, a metal sheet closing the opening in said wall and welded to the inner surface of said wall, said sheet having a peripheral flange extending inwardly from said wall and spaced from the others of said walls, and means including resilient material compressed between said flange and said other walls for hermetically sealing said sheet and said cabinet.

3. A cabinet including a plurality of metal walls forming the sides thereof and having flanges at the bottom thereof, a bottom wall for said cabinet comprising a peripherally flanged metal sheet welded to the flanges on said walls at the bottom thereof, and means including a strip of resilient material compressed between the peripheral flange of said sheet and said walls for hermetically sealing said bottom wall and said side walls.

4. A cabinet including a plurality of metal side walls having flanges at the bottoms thereof, a continuous body of resilient material arranged around the bottoms of said side walls on the inner

sides thereof and engaging said flanges, a bottom plate for said cabinet welded to said side walls, and means including a flange on said bottom plate engaging said body of resilient material for compressing said resilient material to form an hermetically sealed joint between said side walls and said bottom plate.

5. A cabinet including a plurality of metal side walls, inturned flanges at the bottoms of said side walls, a bottom plate welded to said flanges, a strip of resilient material arranged around the inside of said walls at the bottoms thereof, and means including a flange on said bottom plate engaging and compressing said resilient strip for forming an hermetically sealed joint between said walls and said plate.

6. The method of forming an hermetically sealed joint between one side of a cabinet structure and the adjoining sides thereof, which comprises forming inturned flanges on said adjoining sides, forming a peripheral flange on said one side, welding said one side to the flanges on said adjacent sides with said peripheral flange spaced from said adjoining sides, filling the space between said sides and said peripheral flange with resilient material, and bending said peripheral flange toward said adjoining sides to compress said resilient material therebetween.
